UNITED STATES PATENT OFFICE.

FREDERICK HEIDBREDER, OF QUINCY, ILLINOIS.

HAY-RACK FOR WAGONS.

SPECIFICATION forming part of Letters Patent No. 781,144, dated January 31, 1905.

Application filed August 10, 1904. Serial No. 220,228.

To all whom it may concern:

Be it known that I, FREDERICK HEIDBREDER, of Quincy, in the county of Adams, State of Illinois, have invented certain new and useful 5 Improvements in Hay-Racks for Wagons; and I do hereby declare the following to be a full, clear, and exact description of the same, reference being had to the accompanying drawings, forming a part of this specification, and to the 10 letters of reference marked thereon.

This invention relates to racks or skeleton bodies for wagons, such as are usually employed for carrying hay or like material of large bulk and light weight, the objects of the 15 invention being to provide a structure of simple and strong construction with which the full width of the wagon-bolsters between the standards may be utilized for the body without the necessity of raising the body above 20 the level of the wheels and without restricting the turning of the front axle, whereby the center of gravity may be lowered, the capacity of the vehicle increased, a wide base secured, and the turning radius of the vehicle 25 reduced to permit of handling in restricted spaces.

In the accompanying drawings, Figure 1 is a perspective view of a wagon having a rack or body thereon embodying the present invention. Fig. 2 is a detail side elevation of 30 a portion of the rack or body. Fig. 3 is a top plan of the parts shown in Fig. 2. Fig. 4 is a section on the line 4-4 of Fig. 2.

Like letters of reference in the several figures indicate the same parts.

The running-gear of the vehicle illustrated is of the usual type employed on farm-wagons and embodies the usual front and rear wheels A and B and the usual bolsters C and D, with 40 their standards c near the ends. The body or rack is formed with longitudinal side pieces or beams E E, spaced apart so as to just fit between the standards c and held rigid by cross-pieces F and F', the latter being located 45 on each side of the bolsters to prevent longitudinal movement of the rack. Each of the side pieces or beams E is preferably surmounted by a longitudinal flat board G, arched over the rear wheels B, and, as is usual in this 50 class of racks, front and rear uprights H and

H' are hinged or otherwise attached to the front and rear ends of the rack to properly position and retain the load. The side pieces or longitudinal beams are necessarily made wide to afford sufficient strength between the 55 bolsters; but when resting directly on the bolsters and the rack is of sufficient width to fill the space between the standards the side pieces will restrict the turning of the front axle on the king-bolt, and hence the wagon can only 60 turn on a long radius. In order to overcome this difficulty without weakening the beams, said beams are cut away or arched out on the under sides to afford a free space for the front wheels, and the arched portion is supported 65 and distortion or twisting of the frame prevented by flanged metal arches K. The arches K are flanged on their upper or convex sides, forming, in effect, channel-irons, between the flanges $\frac{1}{2}$ of which the side beams will fit. Each 70 arched channel-iron is bolted firmly in place, preferably by bolts L, extending vertically through the ends of the iron and through the beam. To secure additional strength, the bolts at one end, preferably the rear end, of the 75 irons may pass through the intermediate top cross-piece of the rack, thereby binding the whole structure firmly together. The ends of the arched channel-irons are usually extended in the same plane or parallel with and fit 80 against the under faces of the flat edges of the beams, as at M, thus forming pockets for confining the portions of the beams most liable to destruction, and at the same time the bolts may extend through the full width of the 85 beams to secure the maximum strength and rigidity. The thickness of the arched channel-irons is such as to impart to the undercut part of the rack a strength at least equal to the uncut portions, and thus while the advantages 90 of a low center of gravity, a wide base, and an undercut body are secured no strength or rigidity is sacrificed.

It will be noted that racks of ordinary construction may be readily converted into undercut racks by simply arching out the side beams and bolting in arched channel-irons such as described, and hence I do not wish to be limited in respect to the particular type of 95 rack or running-gear employed.

Having thus described my invention, what I claim as new, and desire to secure by Letters Patent, is—

1. A hay-rack for vehicles embodying side beams, arched out on the under side to form an undercut rack for the accommodation of the front wheels and integral arched channel-irons bolted in the arched portions of the beams, with the flanges embracing said beams; substantially as described.
2. A hay-rack for vehicles embodying side beams arched out on the under side to form an undercut rack for the accommodation of the front wheels and connected by cross-
15 pieces, integral arched channel-irons located

in the arched portions of the beams and bolts passing vertically through the ends of the irons and beams at each side of the arched portions; substantially as described.

3. A support for the undercut portion of 20 hay-racks consisting of an arched channel-iron having its ends extended in substantially the same plane and with its flanges projecting from its convex side; substantially as described.

FRED. HEIDBREDER.
